HAIR SECURING DEVICE
Jacob M. Sterner, 1914 Ave. Y, Brooklyn, N.Y.
Filed Dec. 27, 1960, Ser. No. 78,460
1 Claim. (Cl. 132—46)

This invention relates to a hair securing device which is designed to hold a "pony tail" in place upon the head of a girl or woman.

The instant invention is considerably more advantageous than such devices used in the past because it is simple and inexpensive in construction and is automatically adjustable.

Other objects and advantages of the instant invention will become apparent to the reader of this specification and will be set forth in the appended claim.

The invention will be further described by reference to the accompanying drawings which are made a part of this specification.

FIG. 1 is a plan view of a hair securing device made in accordance with this invention.

FIG. 2 is a side view thereof.

FIG. 3 is a sectional view thereof taken along lines 3—3 of FIG. 2.

FIG. 4 is a perspective view of the hair securing device of this invention in place upon the head of a wearer, the device being shown as securing a pony tail in place.

FIG. 5 is a sectional view of the invention shown in FIG. 4 taken along lines 5—5 of FIG. 4.

Referring now to the specific form of the invention as set forth in the accompanying drawings, the hair securing device of this invention 11 is formed with a support 12. Support 12 is provided with an opening 13 adjacent each of the corners 14 thereof.

Approximately in the center of support 12 is projection 15 which is formed with an overhanging roof portion 16.

First flexible hair embraceable member 17 is formed with forwardly extending bifurcated portions 18 and is secured to support 12. Bifurcated portions 18 are in turn secured at their portions forward of support 12 by first junction member 19. First junction member 19 in turn secures second hair embraceable member 20 which in turn is divided into forwardly extending bifurcated portions 21. Second junction member 22 is forward of first junction member 19 and secures the forward bifurcately-extending portions 21 of second hair embraceable member 20 to one another.

In operation base portion 12 is placed alongside the pony tail 23 of the wearer and first hair embraceable member 18 wrapped around the said pony tail 23 until the portion 24 immediately rearward of first junction member 19 is brought into engageable position with projection 15 upon support 12. At this point the device remains in place as shown in FIG. 5. The device is grasped by the user by holding second hair embraceable

2

member 20 by its bifurcated portions 21 which allows the device to be easily wrapped around the hair of the user. If, on the other hand, the hair has a larger diameter than can be conveniently accommodated by the engagement of the portions previously referred to, it is also possible to engage the area 26 immediately behind second junction member 22 with projection 15.

In order to obtain the best operation of the instant device and to insure that the device will remain about the hair of the wearer in firm position and will not be accidentally displaced, it is preferable to make first hair embraceable member 17 of elastic material and, in order to further improve the operation of the device, it is preferable to make second hair embraceable member 20 also of elastic material.

The foregoing specific description indicates the manner in which the objects of this invention have been achieved and the operation thereof but the reader is cautioned to note that the specific embodiments and modifications of this invention set forth in the specification herein are for purposes of illustration and for purposes of example only. Various changes and modifications may obviously be made within the spirit and scope of this invention and would occur to those skilled in this art.

25 I claim:

A hair securing device comprising a substantially square support, a projection centrally disposed thereupon, an overhanging roof portion upon said projection, said support being provided with an opening adjacent each corner thereof, a first elastic hair embraceable member passing through said openings above and below said support secured to said support, and bifurcately extending forwardly therefrom, a first junction member joining the forward portions of said bifurcated portions of said first hair embraceable member to one another, a second elastic hair embraceable member secured to said first hair embraceable member by said first junction member and bifurcately extending forwardly therefrom, a second junction member joining the forward ends of said second hair embraceable member to one another, the portions of said hair embraceable members rearward of said first and second junction members being selectively engageable with said projection upon said support.
